UNITED STATES PATENT OFFICE

WILHELM B. BRONANDER, OF MONTCLAIR, NEW JERSEY

FIRE EXTINGUISHER SUPPORT

Application filed March 16, 1928. Serial No. 262,201.

This invention relates to fire extinguisher supports.

More particularly stated, the invention relates to the grenade type of fire extinguisher and to a holder or support for the grenade.

This invention has for its salient object to provide a support for a grenade so constructed that the grenade can be easily and readily removed therefrom and, furthermore, so constructed and arranged that in case of fire the grenade will automatically drop, break, and dispense the fire extinguishing fluid.

Another object of the invention is to provide a bracket or holder for grenades comprising few parts and a structure that can be economically manufactured.

Further objects of the invention will appear from the following specification taken in connection with the drawings, which form a part of this application, and in which

Fig. 1 is an elevational view of support constructed in accordance with the invention showing a grenade supported thereby;

Fig. 2 is a sectional elevation showing the pivotal support of the grenade retaining member;

Fig. 3 is an elevational view similar to Fig. 1 but showing a slightly modified form of the invention.

This invention briefly described consists of a support for fire extinguisher grenades having means connected to a bracket or plate for engaging and supporting the grenade. The supporting means consists of a pair of members which engage the grenade and are conjointly effective in supporting the grenade in position, one of the members being movable and being held in grenade engaging position by fusible means adapted to melt or give way in case of fire.

Further details of the invention will appear from the following description.

In the form of the invention illustrated in Figs. 1 and 2, the grenade support comprises a bracket or plate 10 having a shelf 11 struck out from the material thereof and bent laterally and provided with an open-

ing 12 for receiving the lower end of the grenade. An arm or grenade retaining member 15 is pivoted on lugs 16 formed on the bracket 10 and has its outer end dished, as shown at 18. A spring 20 is carried by the pivot pin 21 on which the arm 15 is pivoted and one end of the spring engages the bracket 10 and the other end engages the arm 15. The spring 20 tends to raise the arm 15 but the arm is held in engagement with the top of the grenade by a fusible link 23 connected at one end to a lug 24 carried by the arm and connected at the other end to a lug 25 carried by the plate 10.

It will be noted that the arm 15 is longer than the shelf 11 and the grenade is therefore supported in inclined position. In case of fire the fusible link 23 will melt, thus releasing the arm 15 which will be swung upwardly by the spring and the grenade will fall and break.

The structure shown in Fig. 3 is similar to that shown in Fig. 1 except that the shaft 31 is pivoted at 32 to the bracket 10 and is held in engagement with the lower end of the grenade by a fusible link 33. The arm 35, preferably formed of resilient material, is secured at 36 to the plate 10 and the dished end 38 rests on the top of the grenade.

In case of fire the shelf 31 will be released by the fusible link and will swing downwardly on its pivot, thus releasing the grenade.

It will be obvious that a grenade supported as shown in Figs. 1 to 3 can be easily removed from the support by a lateral pull or by lifting the grenade slightly to release the lower end from the opening in the shelf.

By the term "grenade" as used in the specification and claims is meant a frangible container having a fire extinguishing fluid therein.

Although certain specific embodiments of the invention have been particularly shown and described, it will be understood that the invention is capable of modification and that changes in the construction and in the

arrangement of the various cooperating parts may be made without departing from the spirit or scope of the invention, as expressed in the following claims.

5. What I claim is:

1. A support for fire extinguisher grenades comprising a supporting element, a shelf member extending laterally therefrom and adapted to engage a grenade from below, a second member thereon adapted to engage the grenade from above, said members conjointly acting to support said grenade, one of said members being movable and of such length relative to the other mem-

10 10 members conjointly acting to support said grenade, one of said members being movable and of such length relative to the other mem-

15 15 bers as to position the grenade in outwardly inclined relation to the supporting element whereby the grenade may drop upon release by said movable member, and heat responsive means to hold said movable member in engagement with the grenade.

20 20 2. A support for fire extinguisher grenades comprising a supporting element, a shelf member extending laterally therefrom and adapted to engage a grenade from be-

25 25 low, a second member connected to said sup- porting element adapted to engage the grenade from above, said members conjointly acting to support said grenade, one of said members being movable and of such length relative to the other member as to

30 30 position the grenade in outwardly inclined relation to the supporting element, whereby the grenade may drop upon release by said movable member, and fusible means to hold said movable member in engagement with the grenade.

35 35 3. A support for fire extinguisher grenades comprising a supporting element, a pair of members carried by said element and located to engage the ends of the grenade and to support the same by cooperation with each other, and heat responsive means for holding a movable one of said members in position to engage the grenade, the grenade

40 40 engaging portions of said members being positioned relative to each other to support the grenade in outwardly tilted position relative to the supporting element.

45 45 4. A support for fire extinguisher grenades, comprising a plate, a pair of members carried by said plate and located to engage the ends of the grenade and to support the same by cooperation with each other, one of said members being pivotally connected to

50 50 the plate and fusible means for holding said pivoted member in position to engage the grenade, the grenade engaging portions of said members being positioned relative to each other to support the grenade in out-

55 55 wardly tilted position relative to the plate.

60 60 5. A support for fire extinguisher grenades comprising a bracket, a shelf member extending laterally therefrom and having a portion positioned to receive the lower end

65 65 of a grenade, a member connected to the

bracket and having a dished outer end positioned to engage and rest on the grenade to support the grenade by cooperation with the said shelf member, said dished member being spaced from the plate a sufficient distance to hold the grenade in upwardly and outwardly inclined position relative to the plate, and fusible means connected to a movable one of said members and to the bracket for holding said member in engagement with the grenade.

70 70 6. A support for fire extinguisher grenades comprising a bracket, a shelf member extending laterally therefrom and having an opening positioned to receive the lower end of a grenade, a member connected to the bracket and having a dished outer end positioned to engage and rest on the grenade, the grenade engaging portions of said members being positioned relative to each other to conjointly support the grenade in upwardly and outwardly tilted position relative to the plate and fusible means connected to a movable one of said members and to the bracket for holding said member in engagement with the grenade.

75 75 7. A support for frangible fire extinguisher grenades comprising a plate, a pair of vertically spaced, laterally extending grenade retaining members carried by said plate, conjointly effective to support the grenade, one of said members being movable from grenade holding position, the upper one of said members extending a sufficiently greater distance from the plate than the other member as to permit a supporting of the grenade in outwardly tilted position and fusible means engaging said plate and said movable member for holding said member in engagement with the grenade.

80 80 8. A support for frangible fire extinguisher grenades comprising a plate, a pair of vertically spaced, laterally extending grenade retaining members carried by said plate, conjointly effective to support the grenade the upper one of said members being movable and extending a sufficiently greater distance from the plate than the other member as to permit a supporting of the grenade in outwardly tilted position and fusible means engaging said plate and the upper one of said members for holding said member in engagement with the grenade.

85 85 9. A support for frangible fire extinguisher grenades comprising supporting means, a pair of vertically spaced, laterally extending grenade retaining members carried by said means, conjointly effective to support the grenade, the lower one of said members being movable and extending a sufficiently lesser distance from the supporting means than the other member as to permit a supporting of the grenade in outwardly tilted position and fusible means engaging said means and the lower one of said

- members for holding said member in engagement with the grenade.
10. A support for frangible fire extinguisher grenades comprising a supporting element, a pair of vertically spaced, laterally extending grenade retaining members carried by said element and conjointly effective to support a grenade, the lower of said members being movable relative to said supporting element and away from said other member, and fusible means engaging said supporting element and said lower member for holding said member in grenade supporting position.
11. A support for frangible fire extinguisher grenades comprising a supporting element, a pair of vertically spaced, laterally extending grenade retaining members carried by said element and conjointly effective to support a grenade, the lower of said members being pivoted on said supporting element and movable away from said other member, and fusible means engaging said supporting element and said lower member for holding said member in grenade supporting position.
12. A support for frangible fire extinguisher grenades comprising a supporting plate, a shelf member extending laterally therefrom and adapted to receive the lower end of a grenade, and a member carried by the plate and of a sufficient length to extend over the top of the grenade and to hold the grenade on the shelf in a position inclined outwardly away from said plate, said members being conjointly effective to support the grenade, one of said members being movable to release the grenade, and heat responsive means normally retaining said movable member in grenade engaging position.
13. A support for frangible fire extinguisher grenades comprising a supporting plate, a shelf member extending laterally therefrom and adapted to receive the lower end of a grenade, and a curved member carried by the plate and of a sufficient length to extend over the top of the grenade and to hold the grenade on the shelf in a position inclined outwardly away from said plate, said members being conjointly effective to support the grenade, one of said members being movable to release the grenade, and heat responsive means normally retaining said movable member in grenade engaging position.
14. A support for frangible fire extinguisher grenades comprising a supporting plate, a shelf extending laterally therefrom and adapted to receive the lower end of a grenade, a movable member carried by the plate and of a sufficient length to extend over the top of the grenade and to hold the grenade on the shelf in a position inclined outwardly away from said plate and fusible
- means for holding said member in grenade engaging and holding position.
15. A support for frangible fire extinguisher grenades comprising a supporting plate, and a pair of members carried by said plate and projecting laterally therefrom, one of said members being movable to grenade releasing position, restraining means therefor, effective under the action of heat to release said member, said members having portions adapted to engage the top and bottom of a grenade and conjointly support the grenade in upright position, the grenade engaging portion of the upper member being spaced a sufficiently greater distance from the plate than the grenade engaging portion of the other member, as to support the grenade in a position to drop by gravity upon release thereof by said movable member.
16. A support for frangible fire extinguisher grenades comprising a supporting plate, a pair of members carried by said plate and projecting laterally therefrom, one of said members being movable to grenade releasing position, restraining means therefor, effective under the action of heat to release said member, said members having portions adapted to engage the top and bottom of a grenade and conjointly support the grenade in upright position, the grenade engaging portion of the upper member being spaced a sufficiently greater distance from the plate than the grenade engaging portion of the other member, as to support the grenade in a position to drop by gravity upon release thereof by said movable member.
17. In a fire extinguisher, a grenade holder comprising an upright member, a shelf connected to the upright member and disposed at an oblique angle to its vertical plane upon which the grenade may be releasably seated and a retaining member fusibly connected to the upright member for overlying and embracing or partly embracing the grenade.
18. In a fire extinguisher, a grenade holder comprising an upright member, a shelf connected to the upright member and disposed at an angle to its vertical plane, said shelf having a downward-forward inclination and a retaining member fusibly connected to the upright member for overlying and embracing or partly embracing the grenade.
19. In a fire extinguisher, a grenade holder comprising an upright member, a shelf, connected to the upright member and disposed at an oblique angle to its vertical plane, on which the grenade may be seated, said shelf having an apertured recess for the base of the grenade, and a retaining member fusibly connected to the upright member.

for overlying and embracing or partly embracing the grenade.

20. A support for frangible fire extinguisher grenades comprising a supporting element and a pair of laterally extending, coacting grenade retaining members, one of said members being arranged to extend over the upper portion of a grenade and the other member having an opening to receive the lower portion of the grenade and being pivoted for movement relative to said supporting element and away from the other member, and heat controlled means for holding the pivoted member against movement on its pivot, the grenade being releasable from the pivoted member upon movement thereof, upon a predetermined rise in temperature.

21. A support for frangible fire extinguisher grenades comprising a supporting element, a pair of laterally extending grenade retaining members carried by said element and conjointly effective to support a grenade, the lower of said members being movable relative to said supporting element and away from said other member, and heat responsive means engaging said supporting element and said lower member for holding said member in grenade supporting position.

30. 22. A support for frangible fire extinguisher grenades comprising a supporting element, a pair of vertically spaced grenade retaining members carried by said element and conjointly effective to support a grenade, the lower of said members being pivoted and movable away from said other member, and heat responsive means engaging said supporting element and said lower member for holding said member in grenade supporting position.

35. 40. In witness whereof, I have hereunto set my hand this 3rd day of March, 1928.

WILHELM B. BRONANDER.
